OTHER PUBLICATIONS

Design U.S. Appl. No. 29/514,414, filed Jan. 12, 2015, entitled "Chalk Reel," Inventor: Anthony Michael DeLeo.

Primary Examiner — Antoine D Davis

(57) **CLAIM**

The ornamental design for a "chalk reel," as shown and described.

DESCRIPTION

FIG. 1 is a perspective view of a chalk reel in a closed orientation, showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of the chalk reel in an open orientation.

The subject matter shown in dashed lines is for illustrative purposes and forms no part of the claimed design.
